UNITED STATES PATENT OFFICE.

FREDERICK B. MCLEAN, OF WRENSHALL, MINNESOTA.

BULL-LEAD.

1,051,428.

Specification of Letters Patent.

Patented Jan. 28, 1913.

Application filed January 24, 1912. Serial No. 673,054.

To all whom it may concern:

Be it known that I, FREDERICK B. MCLEAN, a citizen of the United States, residing at Wrenshall, in the county of Carlton and State of Minnesota, have invented certain new and useful Improvements in Bull-Leads, of which the following is a specification; reference being had to the accompanying drawings.

10 This invention relates to improvements in bull leads and has for its object to provide a device of this character by means of which fractious or unmanageable animals may be readily captured and controlled.

15 Another object of the invention is to provide a bull lead having an open loop or hook on one end to be engaged in the nose ring of the animal, and novel means for closing said hook whereby its accidental or inadvertent opening is rendered impossible.

20 Another object of the invention is to provide a device of this character which is of simple construction, is extremely strong and durable and may be utilized as a weapon of defense in case of necessity.

25 With the above and other objects in view, the invention consists of the novel features of construction, combination and arrangement of parts hereinafter fully described and claimed, and illustrated in the accompanying drawings, in which—

30 Figure 1 is a side elevation partly in section of a bull lead embodying my improvements; Fig. 2 is an enlarged longitudinal section of one end of the device, showing the hook closing rod in its open position; Fig. 3 is an end view; Fig. 4 is a section taken on the line 4—4 of Fig. 1; Fig. 5 is a section taken on the line 5—5 of Fig. 1.

35 40 Referring in detail to the drawing 5 designates the tubular barrel which is formed of iron or other metal and is provided upon one end with interior screw threads to receive the threaded stud 7 of the hook 6.

45 The body of this hook is provided with an angularly extending bore 8 in which the angularly disposed end of the section 9' of the rod 9 is movably disposed. The end of this angular portion of the rod is adapted

50 to extend across the entrance 6' of the hook and engage the bill 6' thereof to close said entrance. The inner end of the rod section 9' is provided with a socket in the wall of which a transverse semicircular slot 9" is formed to receive a pin 9" which is fixed in the end of the main section 9 of the rod

which is rotatably mounted in said socket. The main section of the rod 9 is concentrically disposed within the barrel or body 5 and extends entirely through the same. 50 The other end of this barrel is exteriorly threaded to receive a cap 10. The end wall of this cap is provided with a central opening 11 through which the rod 9 is loosely disposed. The rod 9 is provided at a short 55 distance from its end with an annular flange or collar 12 to which is secured one end of a coiled spring 13, the other end of said spring being secured to the end wall of the cap 10. Upon the rod 9 between the flange 70 12 and the barrel closing cap a short longitudinal rib 14 is formed. In the edge of the opening 11 of the closure cap a groove 15 is formed through which the rib on the hook closing rod is adapted to move. The outer 75 face of the cap 10 at the edge of the opening 11 therein is provided with a recess or depression 16 and the inner face of said cap is also provided with a recess 17 which is diametrically opposed to the recess 16. To 80 the end of the rod 9 a finger ring 18 is loosely connected and by means of this ring the rod 9 is adapted to be drawn through the tubular barrel 5 to open the hook 6 to permit the same to be engaged with the nose ring 85 of the animal.

Upon the cap 10 the oppositely extending curved arms 24 are formed between which a wood hand grip 25 is pivotally mounted. In operating the device the grip 25 is grasped 90 and one finger inserted through the ring 18 whereby the rod 9 may be conveniently actuated.

In the operation of the device, assuming that the rib 14 on the rod 9 is in line with the 95 groove 15 in the end wall of the cap 10, the operator pulls upon the ring 18, thereby drawing said rod through the opening 11 in the cap and placing the spring 13 under tension. After the rib 14 has been drawn entirely through the groove 15, the rod is given a quarter turn so as to engage the end of the rib 14 in the recess 16 of the cap. Pull upon the rod can now be released and said rod is securely held in its open position 100 105 and the spring 13 rotated under compression. After the operator has engaged the nose ring of the animal in the hook 6, the rod 9 is again turned to permit the rib 14 thereof to move inwardly through the 110 groove 15 in the cap as the spring 13 expands. This spring forces the section 9' of

the rod 9 to its closed position across the entrance 6' of the hook. The operator then continues the rotation of said rod and makes another quarter turn after the hook has been closed, to dispose the end of the rib 14 in the recess 17 in the inner face of the cap 10. When the rod 9 is in its closed position with the forward end 9' thereof in engagement with the bill of the hook, the spring 13 is expanded slightly from its normal condition so that after the rod 9 has been rotated to aline the lug 14 thereof with the recess 17, said spring will act to seat the end of the lug in said recess and retain the same in position. The rod is thus held against any accidental turning movement which would aline said rib with the groove 15 of the cap. As the rod and the operating means therefor is entirely inclosed within the tubular barrel 5, the accidental movement of said rod is rendered impossible. This tubular barrel provides a convenient hand grip so that the operator may retain a secure hold upon the same as he leads the animal.

25 In case the animal should become entirely uncontrollable, the lead may be easily and quickly disengaged from the nose ring and owing to its weight will provide a very formidable weapon of defense so that the infuriated animal may be driven off and liability of injury to the user thereby avoided.

From the foregoing it is believed that the construction and operation of the invention will be fully understood.

35 The device may be easily and quickly operated to connect the same to the nose ring of the animal.

As the operating parts are completely inclosed or housed, liability of the accidental release of the device from the nose ring is practically eliminated.

40 The lead is also extremely strong and durable in construction and owing to the few elements employed it will be obvious that the same can be manufactured at comparatively small cost.

45 While I have shown and described the preferred construction and arrangement of the various parts, it will be understood that the invention is susceptible of considerable modification without departing from the essential feature or sacrificing any of the advantages thereof.

Having thus described the invention what 55 is claimed is:—

1. An animal lead comprising a barrel, a hook secured in one end of said barrel, a closure cap for the other end of the barrel, a rod to close said hook longitudinally movable through the barrel and through said cap, means for normally holding the rod in its closed position, and means carried by the rod co-acting with said cap to retain the rod in its open and closed positions.

60 2. An animal lead comprising a tubular

barrel having a hook on one end, a rod longitudinally movable in said barrel to open and close the hook, said rod consisting of two sections, means connecting said sections to permit of the rotative movement of one of them with relation to the other, and means to hold said latter rod section against rotation and retain the rod in its open and closed positions. 70

3. An animal lead comprising a tubular barrel provided with internal screw threads at one end, a hook removably engaged in said threaded end of the barrel, a cap threaded upon the other end of the barrel, a rod longitudinally movable through said barrel and through the cap, a coiled spring on said rod to normally hold the same in its closed position, means connected to the rod to move the same to its open position and place said spring under tension, and a rib formed on said rod, said cap having recesses to receive said rib whereby the rod is retained in its open and closed positions. 75 80 85

4. An animal lead comprising a tubular body, a hook removably engaged in one end of said body and provided with an inclined bore, a rod longitudinally movable in the bore of said hook and in said body, a cap removably engaged on the other end of the body to close the same, a coiled spring arranged on said rod normally acting to yieldingly hold said rod in its closed position, said cap having an opening through which said rod extends and provided with a groove at the edge of said opening, said rod having a rib thereon to move through said groove, said cap being further provided upon its inner and outer faces respectively with a recess at the edge of the opening therein to receive one end of the rib and retain the rod 100 105 in its open or closed positions. 90 95

5. An animal lead comprising a tubular body having a hook on one end, a rod longitudinally movable in said body, said rod consisting of two sections one of which is 110 adapted to close said hook, the inner end of said rod section being provided with a socket having a semicircular slot in its wall, the other of said rod sections being rotatably mounted in said socket and provided with a pin to move in said slot whereby the latter rod section may be rotated with relation to the first named section, means arranged upon the rod normally acting to force the same to its closed position, and means carried by said rod co-acting with means on said body to positively hold the rod in its open or closed position. 115 120

6. An animal lead comprising a tubular barrel having a hook on one end, a rod longitudinally movable in the barrel to close said hook, said rod consisting of two sections, means connecting the rod sections to permit of the limited rotative movement of one section with relation to the other, and 125 130

- means for holding said latter section against rotation at the limit of its movement in opposite directions to retain the rod in its open and closed positions.
- 5 7. An animal lead comprising a tubular barrel having a hook on one end, a rod longitudinally movable in said barrel, a spring yieldingly holding said rod against movement and in its closed position, said rod consisting of two sections, means connecting said rod sections to permit of the limited rotative movement of one section with relation to the other, said latter rod section being longitudinally movable and rotatably

mounted in the other end of the barrel, the 15 end wall of the barrel being provided with a slot, and a rib on said rod section movable through the slot in said end wall and adapted to engage with the opposite faces of the wall to retain the rod in its open or closed 20 positions.

In testimony whereof I hereunto affix my signature in the presence of two witnesses.
